(57) **CLAIM**

The ornamental design for a shape fitting bra, as shown and described.

DESCRIPTION

FIG. 1 is a right perspective view of a shape fitting bra in accordance with the present invention; the broken lines depicted therein illustrating an exemplary human form for display purposes and that forms no part of the claimed design;

FIG. 2 is a left perspective view of the shape fitting bra of FIG. 1;

FIG. 3 is a front elevational view of the shape fitting bra;

FIG. 4 is a right-side elevational view of the shape fitting bra of FIG. 3, shown in a flat position;

FIG. 5 is a left-side elevational view of the shape fitting bra of FIG. 3, shown in a flat position;

FIG. 6 is a top plan view of the shape fitting bra of FIG. 3;

FIG. 7 is a bottom plan view of the shape fitting bra of FIG. 3;

FIG. 8 is a rear elevational view of the shape fitting bra of FIG. 3; and,

FIG. 9 is a perspective view of the shape fitting bra of FIG. 3.

The clasps shown with broken lines in FIGS. 1-3, 6-7, and 9 on the front of the bra form no part of the claimed design.
